(57) **CLAIM**

The ornamental design for a Bluetooth converter, as shown and described.

DESCRIPTION

FIG. 1 is a perspective view of the Bluetooth converter showing my new design;

FIG. 2 is a front view of the Bluetooth converter;

FIG. 3 is a rear view of the Bluetooth converter;

FIG. 4 is a left view of the Bluetooth converter;

FIG. 5 is a right view of the Bluetooth converter;

FIG. 6 is a top view of the Bluetooth converter; and,

FIG. 7 is a bottom view of the Bluetooth converter.

The surface(s) or poration(s) of the article shown in broken lines in the drawings being for illustrative purpose only and forming no part of the claimed design.
